UNITED STATES PATENT OFFICE.

JOSEPH E. PERRAULT AND LOUIS J. SCHROEDER, OF WATERTOWN, MASSACHUSETTS,
ASSIGNORS TO HOOD RUBBER COMPANY, OF WATERTOWN, MASSACHUSETTS, A
CORPORATION OF MASSACHUSETTS.

BOOT TREE OR LAST.

Application filed May 14, 1925. Serial No. 30,275.

To all whom it may concern:

Be it known that we, JOSEPH E. PERRAULT and LOUIS J. SCHROEDER, citizens of the United States, and residents of Watertown, in the county of Middlesex and State of Massachusetts, have invented certain new and useful Improvements in Boot Trees or Lasts, of which the following is a specification.

10 Our present invention relates to improvements in boot trees or lasts of the type used in the manufacture of rubber boots, and aims to provide a simple, economical and efficient article in which the toe piece will be securely held to the main body or leg portion during manipulation and boot manufacture, but can be readily unlocked to permit removal of the last.

20 The invention further aims to provide a construction in which the means utilized for unlocking the toe portion will also function to admit fluid under pressure between the last and boot whereby the latter will be blown or forced free from the last to facilitate withdrawal.

25 With these and other objects in view the invention comprises the novel features of construction and arrangement and combination of parts hereinafter described, my said invention being defined by the claims appended hereto.

In order that the invention may be better understood reference is made to the accompanying drawings in which—

35 Fig. 1 is a central vertical section through a tree or last.

Fig. 2 is a sectional detail.

Fig. 3 is a view showing the last with a boot thereon in side elevation (partly broken away at the top) with the actuating valve applied thereto.

Fig. 3^a is a detail sectional view of the valve in starting position.

Fig. 4 is a detail view of the valve in side elevation viewed at right angles to Fig. 3.

Fig. 5 is a sectional view showing a modified form of valve.

Fig. 5^a is a similar view showing the valve of Fig. 5 in starting position.

50 Referring by reference characters to these drawings the toe portion of the last is designated 1 and the main body (including leg

and heel portions) 2, these being made hollow as shown.

The juxtaposed or cooperating faces of the toe section body portion are preferably made of substantially inverted L shape as indicated by the dotted line 3, Figs. 1 and 3.

The said juxtaposed face of toe member 1 carries a centrally arranged rib or flange 4 which may conveniently be formed as a plate or bar member fitted in a groove or recess in the wall of the toe member and secured therein by rivets 5 though if desired it could be formed as an integral part of the toe section. 65 This flange or rib fits in a correspondingly arranged groove or channel in the juxtaposed face of the main leg portion of the last as clearly shown in Fig. 2.

The horizontally turned upper end of the 70 rib 4 has formed in its upper face a recess 4^a which receives a projection 7 carried by the leg portion, such recess being preferably of semi-circular formation and the projection being formed by a rivet member extending 75 through an opening in the leg portion and having one half the portion thereof in line with the slot projecting into the groove or channel to form the key. The lower end of the rib or flange member 4 is projected laterally towards the heel of the last as indicated at 4^b and the upper edge of the offset portion is provided with a recess 4^c designed to receive and cooperate with retaining member in the shape of a transverse pin or rivet 6. 85

The rib or flange 4 is provided with a keeper recess 4^d in the edge facing the leg portion which is adapted to be engaged by a latch member or dog 9 which may conveniently be mounted to have oscillating movement on a pivot pin 11. With the parts in the position shown in Fig. 1 it will be readily seen that the toe section is securely locked to the leg portion, the rib 4 being held by the latch with the recesses 4^b and 4^d in locking engagement with the pins 6 and 7. Withdrawal of the latch 9 will, however, permit the leg portion to be withdrawn vertically and disengaged or separated from the toe section which can thereafter be removed 100 separately.

A convenient means of operating the latch is to provide a rod 14 suitably guided to have a rectilinear movement, said rod hav-

ing a lengthwise slot 14^a into which a portion of the latch projects, said projecting portion being provided with a transverse pin 13 which engages a slot 9^a in the latch member.

Downward movement of the rod towards the sole of the last will rock the latch on its pivot and withdraw it from locking engagement with the keeper slot in toe section. The upper end of the rod 14 is preferably guided in the bore 19^a of a hardened sleeve 19 carried by the top portion of the last such sleeve being provided with lateral ports 19^b for a purpose hereinafter described, and the upper end of the rod projecting slightly above these ports when the parts are in locking position as shown in Fig. 1, said upper end fitting the bore with a substantially air tight fit whereby the rod 14 will function as a piston if fluid pressure is applied to the bore as hereinafter set forth.

The lower end of the rod 14 is slidably held in a recess in the lower end of the last, conveniently in a substantially cylindrical projection or hollow stud 2^a. The lower end of the rod is preferably provided with a reduced portion 14^b which is surrounded by the upper portion of a coiled compression spring 18 the lower end of which bears against a removable screw plug 21. This spring normally holds the rod elevated and the latch in locking position, but downward movement of the rod will rock the latch to unlock the toe section as will be readily apparent.

The rod could be readily operated mechanically by the use of any suitable push tool, but we prefer to provide pneumatic means such for example as that which will now be described, referring to Figs. 3, 3^a and 4 as the air pressure after operating the locking means enters between the last and the boot and assists in stripping the latter. 23 designates a valve casing or body which has a cylindrical bore 23^a which slidably receives a valve member 24, which has an annular groove or channel 24^a communicating by one or more radial ports 24^b with an axial bore or air passage 24^c open at its lower end. A pipe 25 designed to be connected to any suitable source of fluid under pressure (not shown) is connected through a suitable port with the annular channel 24^a and with the parts in the position shown in Fig. 3 fluid under pressure would be free to flow into the space 19^a above the upper end of rod 14 (Fig. 1) and force the latter downward to unlock the last. When the rod has been moved down to unlocking position ports 19^b are uncovered which allows the pressure fluid to enter the interior of the last. This finds its way through the parting line 3 into the space between the boot and last and blows the former free from the last thereby facilitating ready removal.

Normally the valve is held closed as shown in Fig. 3^a to prevent the escape of air or other fluid by compression spring 26 confined between the upper end of the valve body and an annular flange 28^a which may be rigidly connected to member 24, conveniently by forming said flange on a sleeve 28 designed to be slipped over and secured to the projecting upper end of valve member 24 by means such as the threaded connection shown, said sleeve serving as a stop to limit the outward movement of the valve.

In actual practice we find it desirable to make the valve member as a stationary element or fixture and perform the unlocking operation by manipulation of the boot tree, though the reverse is within the scope of my invention.

To this end the last carries at its upper end near one side a substantially inverted L-shaped projection or hook member 32 which is designed to be engaged by a corresponding projection 33 carried by the valve member 24 near the lower end thereof. By interengaging these projections and aligning the lower end of the valve member with the bore 19^a and thereafter bearing down on the toe of the last in the direction of the arrow, Fig. 3, the last will first fulcrum on the interengaging projections 32-33 to align opening 19^a with nipple 24^c and effect an air tight connection by reason of pressure on packing 24^d, and further downward pressure will draw the valve member 24 downward from the position of Fig. 3^a to that of Fig. 3 to bring the ports 25 and 24^c in alignment, admitting compressed air or other fluid in the manner and for the purpose already set forth.

To conveniently enable the last to be unlocked mechanically in case of sticking or failure of air supply, we provide the valve body with an elongated projection 37 of a size and length to enter the bore 19^a and act as a mechanical pusher for the rod 14, so that by aligning bore 19^a with projection 37 and merely pushing on the last unlocking will be effected.

This provides a mechanical locking device which cannot be misplaced by the operator.

In the modification shown in Figs. 5 and 5^a we have disclosed means whereby a pneumatic hammer action may be given to rod 14 to overcome any sticking of the parts. In this form the valve casing 23^a is provided with two air supply pipes 25^x and 25^y and the valve body 24^x is made of cylinder form at its upper end and provided with an axial bore at its lower end within which works a hammer piston 39. Normally spring 26^x holds valve member 24^x with the annular port 24^x out of communication with supply pipe 25^x (see Fig. 5^a) and with port 24^x in communication with supply pipe 25^x.

whereby air enters the interior of the valve member 24^x (piston chamber therein) in front of or below the piston member 39 forcing it upward until arrested by stop 54. The air or fluid above or back of the piston exhausts through port 55 to atmosphere. Now supposing the valve member 24^x to be pulled forward by application of the last in the manner described in connection with Figs. 1 to 4 inclusive, air supply pipe 25^x is cut off from the piston chamber while air pipe 25^y is connected therewith by port 24^y, the stop member 54 moving forward with the valve member so as to cause the upper face of the piston member 39 to be just below the port 24^y as illustrated by the position of the stop 54 in Fig. 5. Air is therefore admitted above or behind piston member 39 driving the latter forward, the air in front of or below the piston exhausting through port 56. No air can escape from the piston chamber into the boot tree until the lateral port 39^b has passed below the lower end of the valve bore as shown in Fig. 5, which is after the hammer action has occurred.

By releasing the pull on the tree the member 24^x may be allowed to return to the position of Fig. 5 which returns the hammer to upper or starting position in readiness to repeat the operation on the same last if necessary, or if the last is removed the parts are set in position for operation on a fresh last.

If the last fails to unlatch a slight release of the pull on the last will allow valve member 24^x to move upward sufficiently to cut off air from pipe 25^y. This will bring annular port 24^y in communication with air pipe 25^x, Fig. 5^a and through the radial port or ports admit air to the front of piston 39 which will move back or upward until arrested by stop 54, at which time the lateral port 39^b will be covered and escape of air to the hollow interior of the last prevented.

If now the last is again manipulated so as to move cylinder member 24^x forwardly air will be cut off from pipe 25^x and admitted from pipe 25^y to the rear of the piston which will be driven forward to deliver a hammer blow.

We claim:

1. The combination with a boot tree or last having a detachable toe section and means for releasably holding said toe section to the last body, of fluid pressure means for simultaneously operating said releasing means and admitting air under pressure between the boot and last for blowing the former clear of the last.

2. The combination with a tree or last having a detachable toe section, latch means for holding said toe section to the last body, rectilinearly movable rod operatively

connected to said latch means, said last having a tubular bore in its upper end in which the upper end of said rod fits, and means for supplying fluid under pressure to said tubular bore.

3. The combination with a hollow tree or last having a detachable toe section and means for releasably holding said toe section to the last body, of guides at the top and bottom of said last body, a rod rectilinearly movable in said guides, said upper guide having a lateral port communicating with the interior of the last body, a spring for normally holding said rod with its upper end above said port, operating connections between said rod and toe section holding means, and means for admitting fluid under pressure to said upper guide.

4. In combination, a last comprising a leg section and a toe section, said last section having upwardly opening recesses adjacent opposite ends of the parting line and said leg section ribs for engaging said recesses, said toe section having a keeper recess intermediate the aforesaid recesses, a latch member movably carried by the leg section and adapted to engage said recess, and means operable from the top of the last for actuating said latch member.

5. In combination, a last comprising a leg section and a toe section, said toe section having a projecting rib at the parting line and disposed in the lengthwise plane of the last and provided with angularly arranged upper and lower ends projecting in opposite directions, said ends being provided with upwardly opening recesses, said leg section having a groove to receive said rib provided with lugs to engage said recesses, the said rib having a keeper recess interposed between said upwardly opening recesses, a latch member movably carried by the leg section to engage said recess, and means operable from the top of the leg section for actuating said latch member.

6. In combination a last comprising a leg section and a toe section, said toe section having a projecting rib at the parting line and disposed in the lengthwise plane of the last and provided with angularly arranged upper ends projecting in opposite directions, said ends being provided with upwardly opening recesses, said leg section having a groove to receive said rib provided with lugs to engage said recesses, the said rib having a keeper recess interposed between said upwardly opening recesses, a latch member pivoted to said leg section and adapted to engage said keeper recess, a rectilinearly movable rod operatively connected with said latch member, guides at the upper and lower ends of the last for holding said rod, a spring tending normally to press said rod, in a direction to hold the latch in toe-lock.

ing position, said upper guide having an open upper end for enabling the application of rod actuating means.

7. In combination a last comprising a leg section and a toe section having a parting line of substantially inverted L-shape, said toe section having a rib projecting centrally from its parting face in the vertical plane of the last which rib has horizontally re- 10 versely projecting upper and lower ends provided with upwardly opening recesses, said leg section having in its parting face a groove to receive said rib and lugs to engage said recesses, said rib having a down- 15 wardly facing abutment on its vertical face a latch member carried by the leg section for engaging said abutment, and means operable from the top of the last for actuating said latch member.

8. The combination with a last comprising a leg section and toe section with means for detachably holding them together, of means for releasing said holding means comprising a plunger rod operatively connected to said holding means, said leg section having a tubular recess in which the upper end of said rod is guided, and a supply valve for fluid under pressure, having a nozzle to fit said tubular recess.

9. The combination with a last comprising a leg section and toe section with means for detachably holding them together, of means for releasing said holding means comprising a plunger rod operatively connected to said holding means, said leg section having a tubular recess in which the upper end of said rod is guided, and a supply valve for fluid under pressure having a nozzle to fit said tubular recess, said supply valve being normally closed to its source of supply and including means whereby it is opened on pressure being applied to the last.

10. The combination with a last comprising a leg section and toe section with means for detachably holding them together, of means for releasing said holding means comprising a plunger rod operatively connected to said holding means, said leg section having a tubular recess in which the upper end of said rod is guided, a stationary valve casing adapted for connection to a source of fluid pressure, a valve movable in said casing and normally held in cut off position, said last and said movable valve having means for detachable connection.

11. The combination with a last comprising a leg section and toe section with means for detachably holding them together, of means for releasing said holding means comprising a plunger rod operatively connected to said holding means, said leg section having a tubular recess in which the upper end of said rod is guided, a stationary valve casing adapted for connection to a source of fluid pressure, a reciprocating valve movable

in said casing, a spring normally retracting said valve to cut off position, said valve having an outlet nozzle to cooperate with said tubular recess, and said last and said valve having interlocking members offset from 70 said valve nozzle in the direction of the toe of the last.

12. The combination with a last comprising a leg section and toe section with means for detachably holding them together, of 75 means for releasing said holding means comprising a plunger rod operatively connected to said holding means, said leg section having a tubular recess in which the upper end of said rod is guided, a stationary valve 80 casing adapted for connection to a source of fluid pressure, a reciprocating valve movable in said casing, a spring normally retracting said valve to cut off position, said valve having an outlet nozzle to cooperate with 85 said tubular recess, and said last and said valve having interlocking members offset from said valve nozzle in the direction of the toe of the last, said stationary valve casing having a projection adapted to enter 90 the tubular recess in the last to actuate the plunger mechanically in case of sticking.

13. In combination, a last comprising a leg section and a toe section, detachable locking means between them by which the leg 95 section can be detached from the toe section, means for releasing the locking means, and a connection between the last and the releasing means for operating the latter when the last is moved, substantially as described. 100

14. In combination, a last comprising a leg section and a toe section, detachable locking means between them by which the leg section can be unlocked from the toe section, a rectilinearly movable rod in said leg 105 section for releasing said locking means, a contact member adapted to contact with said rectilinearly movable rod, a support by which said contact member is carried, and a detachable pivotal connection between the last and said support upon which the last may 110 fulcrum to enable said rectilinearly movable rod and contact member to be brought into engagement.

15. In combination, a last comprising a leg 115 section and a toe section, detachable locking means between them by which the leg section can be detached from the toe section, fluid pressure supplying means for releasing the locking means, and a pivotal connection 120 between the fluid pressure supplying means and the last whereby the last may be seated against said fluid pressure supplying means, said fluid pressure supplying means being controlled by a movement of the last, after 125 the same is seated thereagainst, substantially as desired.

16. In combination, a last having a body section and a toe section, with a detachable connection between them releasable by fluid 130

pressure, means for supplying fluid pressure, including a valve, a support for the last on which it may swing, said last when swung on said support first seating against the fluid pressure supply means, and by a further movement operating the valve to supply the fluid pressure, substantially as described.

17. In combination, a last comprising a leg section and a toe section, detachable locking means between them, fluid pressure means for actuating said locking means, a stationary valve casing, a valve slidable therein for controlling fluid pressure, and having a part for contact with said fluid pressure operated means, and a detachable pivotal connection between the last and the valve casing arranged to one side of the said contact part, whereby the upper end of the last may be seated against the lower end of the said valve to receive fluid therefrom for operating said fluid pressure actuated means, whereby the last may be swung on said pivotal connection to actuate the slidable valve to admit fluid pressure to said fluid pressure actuated means.

18. In combination, a valve for supplying fluid pressure, a last having a toe section and a body section, means for detachably locking said sections together, said locking means being detached by fluid pressure supplied through said valve, and means whereby the movement of the last body in the direction

of its longitudinal axis will operate said valve, substantially as described.

19. In combination, a last having a toe section and a body section with detachable means for holding them together, and fluid pressure operated means for releasing the detachable means, and means for supplying fluid pressure controlled by the movement of the last in the direction of its longitudinal axis, substantially as described.

20. In combination, a last having a toe section and a body section with detachable means for holding them together, fluid pressure operated means for operating the detachable means, and fluid pressure supply means operated by the movement of the last, substantially as described.

21. In combination, a boot having a body section and a toe section with detachable locking means between them, fluid pressure operated means for releasing said locking means, and means for automatically controlling the supply of fluid pressure by moving the last, said fluid pressure exhausting to the interior of the last and thence out between the last and the boot thereon, whereby the boot is blown for stripping from the last, substantially as described.

In testimony whereof, we affix our signatures.

JOSEPH E. PERRAULT.
LOUIS J. SCHROEDER.
